UNITED STATES PATENT OFFICE.

ISIDOR ROSENBLATT, OF BROOKLYN, NEW YORK.

DESIGN FOR A TASSEL FOR LIGHTING FIXTURES.

Application filed February 6, 1928. Serial No. 25,222. Term of patent 3½ years.

To all whom it may concern:

Be it known that I, ISIDOR ROSENBLATT, a citizen of the United States, residing at Brooklyn, in the county of Kings and State of New York, have invented a new, original, and ornamental Design for a Tassel for Lighting Fixtures, of which the following is a specification, reference being had to the accompanying drawing, forming part hereof, in which—

Fig. 1 is a front view showing my new design.

Fig. 2 is a side view.

I claim:

The ornamental design for a tassel for lighting fixtures, as shown.

ISIDOR ROSENBLATT.
